UNITED STATES PATENT OFFICE.

JOSEPH W. PICKENS AND ALBERT J. ROSS, OF JONESBORO, LOUISIANA.

BURGLAR-ALARM.

SPECIFICATION forming part of Letters Patent No. 777,535, dated December 13, 1904.

Application filed August 8, 1904. Serial No. 219,984. (No model.)

To all whom it may concern:

Be it known that we, JOSEPH W. PICKENS and ALBERT J. Ross, citizens of the United States, residing at Jonesboro, in the county of Jackson and State of Louisiana, have invented certain new and useful Improvements in Burglar-Alarms; and we do declare the following to be a full, clear, and exact description of the invention, such as will enable others skilled in the art to which it appertains to make and use the same.

This invention relates to burglar-alarms; and one of the objects of the same is to provide a reliable and efficient circuit-closing device which may be readily attached to a gate or door and which operates to close a circuit whenever the door is opened.

Another object of our invention is to provide a device of simple construction and which may be connected up with a bell for giving an alarm when the circuit is closed upon opening a gate or door.

These and other objects are attained by means of the construction and arrangement illustrated in the accompanying drawings, in which—

Figure 1 is a diagram illustrating a burglar-alarm made in accordance with our invention. Fig. 2 is a front view of a gate-post provided with a spring circuit-closer. Fig. 3 is a rear elevation of the same. Fig. 4 is a transverse section taken through the gate-post and showing the arrangement of our circuit-closing device.

Referring to the drawings for a more particular description of our invention, the numeral 1 represents a gate or door upon which is arranged a spring circuit-closing device. Secured at one side of the gate is a latch-keeper 2, having secured thereto at one end a spring 3, said spring extending away from the latch-keeper at its opposite end and having secured thereto a bolt 4, which extends through the latch-keeper, through the post, and at the opposite side of the post is provided with a contact-nut 5. A slotted plate 6 is secured to this side of the post, and a contact-wire 7 is secured by binding-screws 8 9 at one side of the slotted plate, the contact-nut 5 normally

bearing upon the connection 7. The line-wire 10 is attached to the bolt 4 and is held in place by a nut 11. Secured to a binding-post 12 is a wire 13, and said wires 10 and 13 are covered with waterproof insulation and are led to the ground and extended to the house and wired into a room or rooms provided with a battery 14, extending from thence to a switch 15 and to a bell 16. When the gate 17 is closed, the spring 3 is pressed toward the latch-keeper 2 and the contact-nut 5 is moved out of contact with contact-wire 7, thus breaking the circuit. Should, however, the gate be opened, the spring 3 pulls the bolt outward until the contact-nut bears against the wire 7 and closes the circuit, and thus ringing the bell 16 until the gate is again closed or until the switch 15 is operated to cut out the bell.

It will be obvious that our device may be used in connection with a door as well as a gate and that the latch-keeper 2 may be dispensed with and a plain plate for supporting the spring substituted therefor.

Our invention is of simple construction and can be made available readily for its purpose.

Having thus described our invention, what we claim as new, and desire to secure by Letters Patent, is—

1. A burglar-alarm comprising a latch-keeper, a flat spring secured at one end to said latch-keeper and having its opposite end normally extending away from said latch-keeper, a bolt secured to said spring and passed through the latch-keeper, a contact-nut on said bolt, a contact-plate, electrical connections between the nut and an alarm-bell, and a gate or door adapted to move the spring to break the circuit, substantially as described.

2. A burglar-alarm comprising a gate-post having secured thereon a latch-keeper, a spring secured to said latch-keeper at one end and having its opposite end extending away from said latch-keeper, a bolt secured to said spring and passing through the latch-keeper, a gate-post, a plate on the opposite side of the gate-post having a contact-wire secured thereto, a contact-nut on the bolt, a wire secured thereto by means of a separate nut, a binding-post, a contact-wire and connections between the con-

tact-nut, the binding-post and the battery, a switch, a bell and a gate adapted when closed to move the spring and break the circuit between the contact-wire and contact-nut and to 5 permit the circuit to be closed when the gate is open, substantially as described.

In testimony whereof we have hereunto set

our hands in presence of two subscribing witnesses.

JOSEPH W. PICKENS.
ALBERT J. ROSS.
